(57) **CLAIM**

The ornamental design for a vacuum cleaner, as shown and described.

DESCRIPTION

FIG. 1 is a perspective view of a vacuum cleaner in a used state with a battery attached, showing my new design; FIG. 2 is a right side view with the battery removed for clarity of illustration;

FIG. 3 is a left side view thereof;

FIG. 4 is a front view thereof;

FIG. 5 is a rear view thereof;

FIG. 6 is a top view thereof; and,

FIG. 7 is a bottom view thereof.

The broken lines showing the battery in FIG. 1 are for the purpose of illustrating the environmental structure and form no part of the claimed design.

The broken lines shown in the drawings illustrate portions of the vacuum cleaner that form no part of the claimed design.
